INVENTOR.
W. A. LAMB.

BY
J. L. LAMM
ATTORNEY.

UNITED STATES PATENT OFFICE.

WILLIAM A. LAMB, OF DENVER, COLORADO, ASSIGNOR OF ONE-HALF TO NORMAN S. BALLANTINE, OF DENVER, COLORADO.

SHALE RETORT.

Application filed December 6, 1920. Serial No. 428,737.

To all whom it may concern:

Be it known that I, WILLIAM A. LAMB, a citizen of the United States, residing at Denver, in the county of Denver and State of Colorado, have invented certain new and useful Improvements in Shale Retorts, of which the following is a specification.

This invention relates to shale retorts and its particular object is to provide a retort of simple and efficient construction particularly adapted to effect the vaporization of the volatile constituents of shales, coals and kindred substances, mainly for the purpose of extracting therefrom the different oils such as those used in the operation of internal combustion engines in the production of aniline dyes, asphaltum and other bases.

Another object of the invention is to provide a retort of this character in which the material is subjected to agitative and impelling actions in a continuous operation. Still further objects are to provide in a retort of the above-mentioned type, means for feeding to the combustion chamber thereof the solid residue of the vaporizing process and to supply the same with powdered shale for heating purposes, and still other objects reside in details of construction and novel arrangements and combinations of parts, all of which will appear in the course of the following description.

In the accompanying drawings in the various views of which like parts are similarly designated,

Figure 1 represents a side elevation of my improved retort, part of the heating chamber having been broken away for the purpose of saving space;

Figure 2, a vertical longitudinal section through the retort;

Figure 3, a front elevation of half of the retort, looking in the direction of the arrow A, Figure 1;

Figure 4, an enlarged fragmentary section on the line 4—4, Figure 2; and

Figure 5, a fragmentary section similar to that shown in Figure 2, showing a modified construction of the heated floor of the vaporizing chamber, upon which the material under treatment is supported.

Referring in detail to the drawings, the reference character 2 designates a structure made up of fire brick or other non-conductive and heat resisting material, which is divided by a longitudinally inclined floor 5

into a combustion chamber 6 and a superposed vaporization chamber 7. The combustion chamber is, as usual, divided by a bridge wall 8 into two compartments 9 and 10, one of which contains a grate 12 for the support of fuel, and the other of which connects with a stack 13 for the escape of smoke and other products of combustion. A valve-controlled nozzle 14, projecting into the fire compartment 9, is connected to a conduit 15 for the injection of powdered shale by the force of compressed air or other impelling agents and one or more doors 16 in the front of the furnace, afford access to the fire when it is desired to replenish the same by the use of other fuel.

The floor of the vaporizing chamber has a series of transversely extending, trough-like depressions 17, divided by ridges 18 of rounded form. In these troughs are disposed rotary agitating and impelling elements 19 which, in the process of vaporization, function to stir the material under treatment and advance it successively from one trough to another throughout the series. Each element consists of two disks 20, coaxially mounted at opposite ends of a shaft 21, which is rotatably supported in boxes 22, mounted in recesses 23 in the side walls of the structure. Connected between the disks 20 at the peripheries thereof are alternately arranged stirring members and impelling members which, during the rotation of the elements, move close to the conical surfaces of the troughs in which the elements are disposed.

The impelling members consist, in their preferred form, of blades 24, which slant in the direction of the rotation of the elements to advance the material to the succeeding trough without lifting the same to a detrimental extent from the heated surface of the retort, and the agitating members consist of blades 25 which are toothed at their outer edges to plow through the material for the thorough division and intermixture of the particles of which it is composed.

The recesses in the walls of the structure in which the boxes are mounted are closed by upwardly moving slide doors 26 which, when opened, afford access to the parts of the mechanism for their lubrication, adjustment and repair. The floor 5 is preferably made of cast iron in adjoining sections which at their ends are set into the side walls.

walls of the structure but it may, if so desired, be composed of fire brick or of cement, or other plastic material as shown at 27 in Figure 5 of the drawings. The roof 28 of the vaporizing chamber has upwardly extending chimneys 29 in sufficient number to permit of the free and immediate escape of the generated gases and they are connected to a flue 29^a which conducts the volatile 10 product of the process to a receptacle in which it is condensed for the recovery of its oleic constituents.

The raw material is fed into the vaporizing chamber at the upper end of its inclined 15 floor through a hopper 30, provided with a suitably constructed gate 31, and the residue of the vaporizing process is discharged from the chamber at the opposite end of the floor, through an opening 32 in the front wall of 20 the structure, connecting with an externally arranged hopper 33.

The hopper has an outlet port 34 in communication with a cylindrical valve housing 35 which, in its bottom portion, has a second similarly formed port 36, which connects with a chute 37, passing through an opening in the front wall of the furnace into the fire compartment of the combustion 30 chamber of the same. A hollow cylindrical 35 valve 38, rotatably fitted in the housing, has in its circumferential wall a port 39, adapted to register successively with the ports 34 and 36 whereby to alternately receive the contents of the hopper and deliver it into 35 the chute.

It will be seen that the valve thus constructed and arranged provides a medium for the continuous discharge of the residue from the floor of the vaporizing chamber 40 while the latter is sealed against the escape of gases.

The agitating and impelling elements and the rotary valve are connected for synchronous rotation in the same direction by 45 an operating mechanism preferably composed of a power shaft 40, mounted in bearings at the rear end of the structure, a line shaft 41 supported in boxes at a side of the same and connected with the power shaft 50 through the medium of a pair of miter gears 42 and 43, pairs of cooperating bevelled gear wheels, the members 44 and 45 of which are respectively mounted on a line shaft, and at the protruding ends of the 55 shafts 21 of the elements 19 and a transmission chain 46, trained over sprocket wheels 47 and 48 which are connected with the shaft of the last element of the series at the lower end of the floor of the vaporizing 60 chamber and with the shaft of the rotary valve 38.

In the operation of the retort, the shale or other material fed in a finely divided condition from the hopper 30 onto the floor 65 of the vaporizing chamber falls into the

first trough of the series, whence it is moved into the next succeeding trough by the impelling action of the blades 24 on the corresponding rotary element. The material is in this manner moved successively from one trough to another throughout the series and, during its said movement, is constantly stirred and divided by the action of the agitating blades.

The floor, which is heated by the fire in the combustion chamber, has its highest temperature at the bottom of the trough-like depressions and the material passing from one depression to another, is thus repeatedly retarded at those points of the floor at which they are most subjected to the vaporizing heat. The impelling blades of the rotary elements not only cause the material to be advanced from one trough to another but also scrape the bottom surfaces of the troughs so as to prevent the adherence of viscous matter and both the impellent members and the agitating members prevent solidification of the material and effect a continuous separation of the particles thereof to admit of a free circulation of the heat and thereby expedite the complete gasification of their volatile constituents.

The residue of the process is, as stated before, fed into the combustion chamber of the furnace to be used as fuel and after its combustible matter has been consumed it is removed from the furnace and treated for the manufacture of fertilizing substances, paint bases, etc. The vapors generated in the retort escape through the chimneys into the flue 30 and, as mentioned hereinbefore, are subsequently condensed for the recovery of their oleic constituents.

Having thus described my invention, what I claim and desire to secure by Letters-Patent is:

1. In a retort of the character described, a vaporizing chamber having recessed side-walls and a floor between them, rotary impelling and agitating elements above said floor, boxes in said recesses, supporting said elements, doors closing the recesses, and mechanism exteriorly of the chamber for the rotation of the elements.

2. A retort comprising a vaporizing chamber having a heated floor provided with transverse depressions, and rotary elements in said chamber, each having alternate series of radiating blades to engage with material in said depression, the blades of one series being toothed at their peripheral edges for the agitation of the material, and the blades of the other series being smooth-edged to impel the same across an edge of the depressions.

3. A retort comprising a vaporizing chamber having a heated floor provided with transverse depressions, and rotary elements in said chamber, each having alter-

nate series of radiating blades to engage with material in said depressions, the blades of one series being toothed at their peripheral edges for the agitation of the material, and the blades of the other series being slanted to impel the same across an edge of the depressions.

4. A retort comprising a vaporizing chamber having a heated floor provided with a transverse depression, and an element in said chamber mounted to rotate about an axis longitudinal of said depression, and comprising longitudinally extending agitating blades and impelling blades alternately disposed to separately and successively engage with material in the depression.

5. A retort comprising a vaporizing chamber having a heated floor provided

with a succession of transverse troughs, and a rotary element in each trough, including an agitating member and a member adapted to cause agitated material to leave the trough and advance to the next following trough.

6. A retort comprising a vaporizing chamber having a heated floor provided with a succession of transverse troughs, and a rotary element in each trough, including a member adapted to agitate material in the trough in the direction of the length thereof, and a member adapted to cause the agitated material to leave the trough and advance to the next following trough.

In testimony whereof I have affixed my signature.

WILLIAM A. LAMB.
